UNITED STATES PATENT OFFICE

117,796

DESIGN FOR A COMBINED FENDER AND
SKIRT AND CHAIN GUARD

John R. Morgan, Oak Park, Ill., assignor to Sears,
Roebuck and Co., Chicago, Ill., a corporation
of New York

Application August 28, 1939, Serial No. 86,917

Term of patent 7 years

To all whom it may concern:

Be it known that I, John R. Morgan, a citizen of the Republic of Guatemala, residing at Oak Park, in the county of Cook and State of Illinois, have invented a new, original, and ornamental Design for a Combined Fender and Skirt and Chain Guard, of which the following is a specification, reference being had to the accompanying drawing, forming a part thereof.

Fig. 1 is a side elevation of a combined fender and skirt and chain guard embodying my new design.

Fig. 2 is an opposite side elevation of the same on a reduced scale.

Fig. 3 is a plan view of Fig. 1.

Fig. 4 is a front elevation of the same.

Fig. 5 is a rear elevation of the same.

I claim:

The ornamental design for a combined fender and skirt and chain guard, substantially as shown.

JOHN R. MORGAN.
